(57) **CLAIM**

The ornamental design for a child seat for automobile, as
shown and described.

DESCRIPTION

FIG. 1 is a perspective view of the child seat for automobile
showing my new design;

FIG. 2 is a front elevational view of FIG. 1.

FIG. 3 is a rear elevational view of FIG. 1.

FIG. 4 is a left side elevational view of FIG. 1.

FIG. 5 is a right side elevational view of FIG. 1.

FIG. 6 is a top plan view of FIG. 1; and,

FIG. 7 is a bottom plan view of FIG. 1.

The broken lines in the drawings depict portions of the child
seat for automobile that form no part of the claimed design.
